UNITED STATES PATENT OFFICE.

ERNEST G. WAGNER, OF LEWISTON, IDAHO.

VALVE CONSTRUCTION.

1,191,046.

Specification of Letters Patent. Patented July 11, 1916.

Application filed January 23, 1914. Serial No. 813,939.

To all whom it may concern:

Be it known that I, ERNEST G. WAGNER, a citizen of the United States, residing at Lewiston, in the county of Nez Perce and State of Idaho, have invented a new and useful Valve Construction, of which the following is a specification.

The present invention appertains generally to valves, and aims to provide a novel and improved valve construction, especially as over the valve construction disclosed in the co-pending application, filed November 12, 1913, Serial No. 800,634.

It is the primary object of the present invention to provide a valve construction embodying a unique assemblage of parts, so that the valve may be readily opened by force, but will be seated by the pressure of the water or other fluid alone, whereby it is impossible for an inexperienced person to jam the valve against its seat, means also being provided for independently actuating the valve to pulverize or eject any accumulations of foreign or extraneous matter between the valve and its seat.

Another object of the present invention is to provide a valve construction of the nature indicated, which will be comparatively simple, substantial, durable, compact and inexpensive, as well as convenient, and efficient in its use.

With the foregoing general objects outlined, and with other objects in view, which will be apparent as the nature of the invention is better understood, the present invention resides in the combination and arrangement of parts and in the details of construction hereinafter described and claimed, it being understood that changes in the precise embodiment of the invention herein disclosed can be made within the scope of what is claimed without departing from the spirit of the invention.

The invention has been illustrated in its preferred embodiment in the accompanying drawing, wherein the figure is a longitudinal central section of the valve construction.

In carrying out the present invention, there is provided a cylindrical body or casting 1, preferably in the form of a casting, and which has one end open. The body or casting 1 is provided with a lateral inlet port or tap 2 adjoining its open end, and with an opposite lateral discharge port or tap 3, into which is inserted, a collar or nipple 3^a hav-

ing a flange 3^b seating against the boss around the outlet opening 3. Thus, the inlet port 2 may be threaded or engaged to a male element or nozzle, for connecting the valve construction to a hydrant, or other source of water or fluid, while the female coupling element of a hose, or the like, may be engaged over the collar or nipple 3^a.

The body or casing 1 is provided intermediate the inlet and outlet ports with internal threads 4, into which is engaged a ring or annulus 5, forming a valve seat, which is preferably provided with a conical or beveled face at that side adjacent the inlet port 2. The annulus 5 is also preferably provided with a plurality of sockets 5^a adjoining the bevel, for facilitating the application and removal of the valve seat to and from the body or casing, the valve seat or ring being readily removed or inserted through the lower or open end of the casing, which open end is normally closed by a cap or screw plug 6.

The upper or closed end of the body or casing 1 is provided with an inwardly projecting or depending sleeve or socket portion 7, disposed axially or concentrically within the casing or body 1, and having a bore 8 therethrough, and opening through the upper end of the casing. The sleeve 7 projects inwardly from the closed end of the casing to a point close adjacent the valve seat. The upper end portion of the bore 8 is counterbored or enlarged to form a stuffing box 9, into which is threaded or engaged a gland 10, to compress the packing 11 within the box 9, against a tubular or hollow stem 12 passed through the bore 8, and threadedly engaged to the lower end portion of the bore 8, as at 13. The screw threads between the sleeve 7 and stem 12 are spaced from the stuffing box to prevent the threads from injuring the packing 11.

A stem 14 is slidable through the tubular stem 12, to be guided thereby, and a valve or valve head 15 is secured to the lower end of the stem 14 to seat upwardly against the valve seat 5, the valve being preferably conical or beveled about its margin to snugly fit the valve seat. The lower end of the tubular stem 12 projects below the sleeve 7, to cooperate with the valve, and the upper end of the stem 12 projects beyond the upper end of the casing, the stem 14 passing snugly through the stem 12 to be guided thereby.

The valve stem 14 being slidable freely through the tubular stem 12, permits the valve to be seated by the pressure of the water or fluid entering the port 2, the valve being of the check valve type. The valve 15 and stem 12 are arranged at opposite sides of the valve seat.

The upper or outer end of the stem 12 is externally threaded, as at 16, and has engaged thereover, a socket or packing nut or gland 17 containing packing 18, to compress the packing 18 against the upper or outer end of the stem 12 and against or around the valve stem 14.

The stem 12 is provided with a squared or noncircular portion 19 directly below the threaded portion 16, and upon which is engaged the hub of a hand wheel 20, a jam or binding nut 21 being threaded upon the threaded portion 16 to lock or secure the hub of the hand wheel 20 upon the squared or noncircular portion 19 of the stem 12. Thus, the hand wheel 20 facilitates the rotation of the stem 12, when desired; so that the stem may be projected downwardly or retracted upwardly into and out of engagement with the valve 15, for the purposes as will hereinafter more fully appear.

Attached to the upper end of the valve stem 14, is a suitable handle or hand hold 22, which is preferably removable, in order that under ordinary conditions, the upper end of the stem 14 may be nonencumbered, to prevent the said stem from being rotated or drawn upwardly or outwardly. When the handle or lever 22 is applied to the outer end of the valve stem 14, it enables the valve to be rotated and forced upwardly against the valve seat, to pulverize or eject any accumulation between the valve and its seat.

The present valve construction may be employed in divers capacities, such as, for attaching a sprinkling hose to a fire hydrant, for a blow-off for steam boilers, and the like. It is evident that when the inlet port 2 is connected with any source of fluid, the pressure of the fluid will normally seat the valve 16, that is, when the screw or stem 12 is retracted upwardly, to permit the valve to close. To open the valve it is only necessary to run the screw or stem 12 downwardly or inwardly, whereby the tip or inner end of the operating or actuating screw or stem 12 will engage the face of the valve to force the valve away from its seat and against the fluid pressure. This will enable the water or fluid to flow through the annular valve seat and out through the discharge port 3. The valve, being of the check valve type, will close automatically, when the screw or stem 12 is retracted, it being noted that the valve cannot be jammed against the valve seat through the medium of the operating stem 12, which will render it impossible to injure the valve or its seat by inexperienced per-

sons. This is of importance, inasmuch as the jamming of the valve against the seat often results in the destruction or mutilation of the valve or its seat, and which is of disadvantage in other respects.

Although the valve cannot be forced against its seat, through the medium of the actuating stem 12, the valve may be forced upwardly and rotated properly, through the medium of the valve stem or spindle 14, and its handle or lever 22, in order that any sediment or accumulation between the valve and its seat can be pulverized or ejected. The valve stem 14 being smooth and unthreaded, will slide readily through the tubular operating stem 12, whereby the valve can only be forced against the valve seat, by the upward thrust or strain applied to the handle or lever 22. As above indicated the handle or lever 22 is normally removed, in order to prevent the valve from being manipulated through the medium of the valve stem. It is also apparent that as soon as the valve stem is released, the valve will be relieved from the pressure previously applied to the valve stem.

The present device reduces the water friction therein, to a minimum, and is of advantage as over the construction disclosed in the above mentioned application, inasmuch as the operating and grinding stems 12 and 14, respectively, are both disposed at one end of the casing, which enables the valve structure to be constructed more compactly and at less expense. It is also to be noted that both of the stuffing boxes in the present device, are located at the low pressure end of the casing, to effectively avoid leakage, the packing 11 preventing leakage between the operating stem 12 and the sleeve 7, and the packing 18 preventing leakage between the two stems. The valve stem or spindle 14 passing through the tubular operating stem 12, will be guided in an effective manner, in order that the valve will be constrained to slide axially in a true manner to and from the valve seat. Both of the stems being arranged at the upper end of the casing, makes it more convenient to operate the two stems, as above intimated.

From the foregoing, taken in connection with the drawings, the other advantages and capabilities of the present invention will be obvious to those versed in the art, and need not be itemized at length, it being observed that the objects aimed at have been carried out satisfactorily.

Having thus described the invention, what is claimed as new is:—

In a valve construction, an upright casing having a lateral outlet adjacent its upper end, a lateral inlet adjacent its lower end, a valve seat between the inlet and outlet, and a depending sleeve carried by said up-

per end, the upper end portion of the bore of the sleeve being enlarged to form a stuffing box below the upper end of the casing, a packing within said stuffing box, a gland 5 threaded into said stuffing box, a tubular stem slidable through the gland and having screw threads engaging the inner portion of the sleeve bore, the screw threads being spaced below the stuffing box, and a valve seat 10 seatable upwardly against the valve seat

and having its stem slidable freely through the tubular stem.

In testimony that I claim the foregoing as my own, I have hereto affixed my signature in the presence of two witnesses.

ERNEST G. WAGNER.
